Primary Examiner — Ruth McInroy(74) *Attorney, Agent, or Firm* — Abelman, Frayne & Schwab(57) **CLAIM**

The ornamental design for a hand-held pool cleaner, as shown and described.

DESCRIPTION

FIG. 1 is a front, top left side perspective view of the hand-held pool cleaner of our invention;

FIG. 2 is a top view thereof;

FIG. 3 is a front elevation view thereof;

FIG. 4 is a right side elevation view thereof, the left side being a mirror image;

FIG. 5 is a rear elevation view thereof; and,

FIG. 6 is a bottom view thereof.

The elements shown in broken lines form no part of the claimed invention.
